INTERNAL-COMBUSTION PERCUSSIVE TOOL

Charles A. Hirschberg, Mountain Lakes, N. J.

Application July 21, 1948, Serial No. 39,902

13 Claims. (Cl. 123—7)

1

The invention here disclosed relates to percussive apparatus such as rock drills, pavement breakers, pile drivers, tampers and the like.

Objects of the invention are to provide apparatus of this general nature which will utilize the advantageous features of an internal combustion engine but will have a free hammering action, without the restrictions of a rigid connection between the hammer and the cycle controlling portions of the apparatus.

Special objects also are to provide an internal combustion type of power hammer which will consist of but few sturdy parts, free of complicated valve mechanisms and the like.

A further object is to provide full, automatic lubrication of all operating parts.

Other desirable objectives and the novel features of invention by which all objectives are attained are set forth or will appear in the course of the following specification.

The drawings accompanying and forming part of the specification illustrate the structure and operation of a present commercial embodiment of the invention. This disclosure, however, is primarily by way of illustration, it being contemplated that many changes and modifications are possible, all within the true intent and broad scope of the invention as hereinafter defined and claimed.

Figs. 1 and 2 in the drawings are longitudinal sectional views of one of the power hammers, taken on planes at right angles to each other;

Fig. 3 is an enlarged broken sectional detail illustrating construction of the outlet and inlet valves in the head of the inner, compressor piston;

Figs. 4 and 5 are broken horizontal sectional views of the outlet and inlet valves as on substantially the planes of lines 4—4 and 5—5 of Fig. 3;

Figs. 6 and 7 are broken vertical sectional details of the outlet and inlet valves as on substantially the planes of lines 6—6 and 7—7 of Figs. 4 and 5, respectively;

Figs. 8 and 9 are cross sectional views of the machine as on substantially the planes of lines 8—8 and 9—9 of Figs. 1 and 2, respectively;

Figs. 10 to 15 are sectional and partly diagrammatic views illustrating a cycle of operation of the machine.

As shown in Figs. 1 and 2, the machine consists in the main of a working cylinder 20, a free piston 21 operating therein, subjected to explosion forces and delivering power impulses and a crank connected piston 22 within the power piston cooperating with the latter to provide a compression coupling between the two pistons and to accomplish the valving functions required for operation of the machine as an internal combustion engine.

The power piston is shown as carrying a ham-

2

mer 23 at its lower end for striking the steel 24 retained in the guide 25 at the lower end of the cylinder.

In the portable form of machine illustrated, the cylinder is equipped with suitable handles 26 which may carry the controls for the engine.

The inner, fixed stroke piston is shown as having a connecting rod 27 engaged with the crank 28 of the crank shaft 29 journaled, substantially, centrally across the mid-length portion of the working cylinder.

The outer, free piston 21 is shown as arched at 30 in its mid-length portion to pass about the crank shaft bearings 31 and the mid-portion of the working cylinder is enlarged transversely at 32 to accommodate the intermediate enlarged portion of the free piston.

Gibs 33 on the enlarged or widened side portions of the power piston, operating in ways 34 in the sides of the working cylinder, hold this free piston against turning and may serve to limit the extent of its stroke.

The compression coupling between the two pistons is created by providing a check valved suction inlet 35, Fig. 1, in the crank case enlargement of the working cylinder and by equipping the compressor piston 22 with an inlet valve 36, Fig. 2, opening from the crank chamber side of the piston up into the compressor space 37 between the heads of the two pistons.

Air compressed between the pistons is additionally used for scavenging and charging purposes by passing the same through an outlet valve 38, Fig. 2, opening downwardly in the head of the compressor piston into a passage or chamber 39 in this piston ported at 40 to register at proper times with an upwardly inclined through port 41 in the side of the power piston and which latter port, at proper times, registers with the lower end of a bypass 42 in the side of the working cylinder opening at its upper end to a position above the power piston.

Structural details of the inlet and outlet valves 36, 38, are illustrated in Figs. 3 to 7. In each case the valving is effected by a series of flexible strips 43 in the inlet valve and 44 in the outlet valve, confined free to bend and slide between slotted plugs 45, 46 and 47, 48.

At the inlet valve, Figs. 3 and 7, the base plug 45 is cross slotted at 49 and flat on top and the upper plug 46 has cross slots 50 offset from the slots in the base and is concaved at 51 at its under side to permit upward flexure of the valve strips 43. The upper plug is shown as screwed into the head of the piston to secure the valve unit in place and the two elements 45, 46, between which the valve strips are loosely confined may be keyed or rigidly connected together so that the slots in the two will stand in the alternating relation shown in Fig. 3.

The outlet valve 38, Figs. 3 and 6, is generally similar in construction, with slots 52 in the lower disc or base portion offset from the slots 53 in the upper screw plug 48, but in this case the lower face of the upper member is flat and the upper face of the lower member is concaved as at 54, to admit downward flexure of the valve strips 44.

With downward movement of the compressor piston the loose valve strips 43 will bow upwardly due to the tendency to create a vacuum in compression space 37, causing air from the crank chamber to pass up into the compression space 37 between the two pistons and with registry of ports or passages 40, 41, 42, and uncovering of the upper end of bypass 42, air compressed in said chamber will bow the valve strips 44 downwardly to permit passage into the combustion chamber in the head of the working cylinder above the power piston.

A spark plug 55, Fig. 1, is shown set in the head of the working cylinder and this cylinder is shown in Fig. 2 as having a fuel injection inlet 56 in one side and an exhaust port 57 in the opposite side, the latter located to be uncovered by the power piston at proper times in the outstroke of the same.

Air for jetting, in the case of rock drill operation, may be provided by grooving the side of the compressor piston at 58 to pass compressed air also from compression chamber 37 through a port 59 in the power piston and port 60 in the working cylinder through a connection 61 and inlet 62 into the chamber 63 beneath the hammer end of the power piston. Flutes 64 in the hammer extension 23 may serve for passing this air to the drill steel and such flutes may be used additionally or alone, as the case may be, for imparting rotation to the drill holder.

Referring to the diagrammatic views for a more complete understanding of the operation, Fig. 10 illustrates the parts substantially at completion of the compression stroke and firing of the explosive mixture. In this position all ports and valves are closed, with an air cushion trapped in the compression chamber 37 between the heads of the two pistons.

Fig. 11 illustrates the outstroke of both pistons, the compressor piston driven by the air spring confined between the two pistons. In this stroke air taken into the crank case on the previous suction stroke of the inner, compressor piston is being drawn into the compressor space 37. This view also illustrates the position of parts immediately before impact.

Fig. 12 illustrates the approximate position of parts at or immediately after impact, with the power piston opening the upper end of the bypass passage 42 to admit scavenging air from the compression chamber 37 to the explosion chamber, the inner piston port 49 at such time registering with the outer piston port 41 and the latter registering with lower end of bypass 42. Also at such time the power piston has uncovered exhaust port 57. The cylinder at this time may rise, aiding in the quick uncovering of bypass and exhaust port.

Fig. 13 illustrates the follow through of the hammer piston and the cylinder starting to drop on the rebound of the hammer piston. At such time the exhaust port is entirely open but the compressed scavenging air is cut off by further outward travel of the compressor piston in the power piston sufficient to carry port 40 in this piston out of register with port 41 in the power

piston. With flow of scavenging air thus shut off, air from the crank chamber is admitted by inlet valve 36 into compression chamber 37 between the pistons for compression.

Fig. 14 illustrates rebound of the hammer piston and commencement of the compression stroke of both pistons, all valving passages or ports being closed in this portion of the cycle.

Fig. 15 illustrates the relation of parts substantially at the moment of fuel injection at 56 and during continuation of compression of the air trapped in the explosion chamber and the air cushion trapped between the power and compressor pistons.

Full automatic lubrication of all operating parts is effected in the illustration by constructing the lower end of the power piston as a well or reservoir 65 for lubricant, it being noted that the open sides 30 of this piston provide access 20 of such oil to the walls of the containing cylinder. This splash system of lubrication aids in cooling the parts. Lubricant in the splash well may be replenished through the crank case air inlet at 35 or a special oil filler opening may be 25 provided in the side of the crank case portion of the working cylinder, normally closed by a suitable plug as indicated at 66 in Fig. 1. A flywheel and the rotary elements of a magneto, fuel injection pump and any other required accessory elements may be mounted on the exposed end or ends of the crank shaft.

The mounting of the crank shaft directly across the mid-portion of the working cylinder and the arching of the mid-portion of the hammer piston about the crank shaft provides a particularly compact close-dimensioned structure which can be light and small enough for ready portability and easy handling. The parts are of rugged design and the only part subjected to hammer action, that is, the power piston, operates freely in the working cylinder, disconnected from the crank shaft except for the indirect air cushion coupling with the compressor piston.

While referred to herein generally as a power hammer, it will be realized that the invention is applicable to mechanisms broadly of combined reciprocating and rotary type here indicated.

What is claimed is:

1. A power hammer comprising a working cylinder, a crank shaft journalled across the mid-portion of said cylinder, a power piston operating in said cylinder and arched in its mid-portion about said crank shaft, a compressor piston operating in said power piston and connected with said crank shaft, cooperative means on said working cylinder, power piston and compressor piston for effecting intake and compression of air between said pistons and transfer of air so compressed between the pistons into the working cylinder above the power piston, said means including intake and outlet valves in the compressor piston, a passage from the outlet valve through the side of the compressor piston, a through port in the power piston to register with the end of said passage in the compressor piston and a passage in the working cylinder ported at one end to register with said through passage and ported at the opposite end to open into the working cylinder above the power piston.

2. A power hammer comprising a working cylinder, a crank shaft journalled across the mid-portion of said cylinder, a power piston operating in said cylinder and arched in its mid-portion about said crank shaft, a compressor

piston operating in said power piston and connected with said crank shaft and cooperative means on said working cylinder, power piston and compressor piston for effecting intake and compression of air between said pistons and transfer of air so compressed between the pistons into the working cylinder above the power piston, the crank containing portion of said working cylinder and the arched mid-portion of said power piston having slidingly engaging keying elements.

3. A power hammer comprising a working cylinder, a crank shaft journalled across the mid-portion of said cylinder, a power piston operating in said cylinder and arched in its mid-portion about said crank shaft, a compressor piston operating in said power piston and connected with said crank shaft and cooperative means on said working cylinder, power piston and compressor piston for effecting intake and compression of air between said pistons and transfer of air so compressed between the pistons into the working cylinder above the power piston, said power piston having a lubricant well at the inner end of the same for effecting splash lubrication of the parts described, the arched mid-portions of said power piston providing access of lubricant to the walls of said working cylinder.

4. A machine in the nature of a power hammer and comprising a working cylinder, a crank shaft journalled transversely across the mid-portion of said working cylinder, a free power piston operating in said cylinder and slotted in its mid-portion to pass the crank shaft, means slidingly keying said free piston in non-rotative relation in the cylinder, a compressor piston operating in said power piston and connected with said crank shaft and means conjointly controlled by said compressor and power pistons for maintaining an air cushion coupling between the heads of said pistons and for passing air so compressed from said air cushion into the working cylinder above the free power piston.

5. A machine in the nature of a power hammer and comprising a working cylinder, a crank shaft journalled transversely across the mid-portion of said working cylinder, a free power piston operating in said cylinder and slotted in its mid-portion to pass the crank shaft, means slidingly keying said free piston in non-rotative relation in the cylinder, a compressor piston operating in said power piston and connected with said crank shaft and means conjointly controlled by said compressor and power pistons for maintaining an air cushion coupling between the heads of said pistons and for passing air so compressed from said air cushion into the working cylinder above the free power piston, said working cylinder having fuel injection and exhaust ports controlled by said power piston.

6. In percussive apparatus having a power generating agency of the internal combustion engine type, a working cylinder, the upper portion of which constitutes an explosion chamber, the central portion of said cylinder having a crank shaft journalled across it, a power piston, the upper portion of which operates in said explosion chamber and by means of an arched section in its mid-portion surrounding said crank shaft is connected to a lower guide piston movable in the lower portion of said working cylinder structure, a striking member projecting axially downwardly from said guide piston to provide an unobstructed free hammering action, and an air compressor

piston operating within said power piston and connected with said crank shaft.

7. In percussive apparatus having a power generating agency of the internal combustion engine type, a working cylinder, the upper portion of which constitutes an explosion chamber, the central portion of said cylinder having a crank shaft journalled across it, a power piston, the upper portion of which operates in said explosion chamber and by means of an arched section in its mid-portion surrounding said crank shaft is connected to a lower guide piston movable in the lower portion of said working cylinder structure, a striking member projecting axially downwardly from said guide piston, to provide an unobstructed free hammering action, an air compressor piston operating within said power piston and connected with said crank shaft, intake and discharge air valves located in the head of said air compressor piston, air discharge ports located in the walls of said compressor and power pistons, timed to coincide at critical points in the movement of said pistons to admit scavenging and fuel mixing air into the explosion chamber of the working cylinder above the power piston, through a switch back porting in the wall of said cylinder.

8. In percussive apparatus having a power generating agency of the internal combustion engine type, a working cylinder, the upper portion of which constitutes an explosion chamber, the central portion of said cylinder having a crank shaft journalled across it, a power piston, the upper portion of which operates in said explosion chamber and by means of an arched section in its mid-portion surrounding said crank shaft is connected to a lower guide piston movable in the lower portion of said working cylinder structure, a striking member projecting axially downwardly from said guide piston to provide an unobstructed free hammering action, an air compressor piston operating within said power piston and connected with said crank shaft, intake and discharge air valves located in the head of said air compressor piston, air discharge ports located in the walls of said compressor and power pistons to admit scavenging and fuel mixing air into the explosion chamber of the working cylinder above the power piston, through a switch back porting in the wall of said cylinder, said cylinder having a fuel injection port leading directly into the combustion chamber, and an exhaust port covered and uncovered by the working piston at different stages in the stroke of the same.

9. In percussive apparatus having a power generating agency of the internal combustion engine type, a working cylinder, the upper portion of which constitutes an explosion chamber, the central portion of said cylinder having a crank shaft journalled across it, a power piston, the upper portion of which operates in said explosion chamber and by means of an arched section in its mid-portion surrounding said crank shaft is connected to a lower guide piston movable in the lower portion of said working cylinder structure, a striking member projecting axially downwardly from said crank shaft, intake and discharge air valves located in the head of said air compressor piston, air discharge ports located in the walls of said compressor and power pistons, timed to coincide at critical points in the movement of said pistons to admit scavenging and fuel mixing air into the explosion chamber of the working cylinder above the power piston, through a switch back porting in the wall of said working cylinder, said cylinder

having a fuel injection port leading directly into the combustion chamber and an exhaust port covered and uncovered by the working piston at different stages in the stroke of the same, the crank containing portion of said working cylinder and the arched mid-portion of said power piston having slidingly engaging keying elements.

10. In percussive apparatus having a power generating agency of the internal combustion engine type, a working cylinder, the upper portion of which constitutes an explosion chamber, the central portion of said cylinder having a crank shaft journalled across it, a power piston, the upper portion of which operates in said explosion chamber and by means of an arched section in its mid-portion surrounding said crank shaft is connected to a lower guide piston movable in the lower portion of said working cylinder structure, a striking member projecting axially downwardly from said guide piston to provide an unobstructed free hammering action, an air compressor piston operating within said power piston and connected with said crank shaft, intake and discharge air valves located in the head of said air compressor piston, air discharge ports located in the walls of said compressor and power pistons to admit scavenging and fuel mixing air into the explosion chamber of the working cylinder above the power piston, through a switch back porting in the wall of said working cylinder, said working cylinder having a fuel injection port leading directly into the combustion chamber, an exhaust port covered and uncovered by the working piston at different stages in the stroke of the same, said power piston having a lubricant well at the inner lower end of the same for effective splash lubrication of the parts described, the arched mid-portions of said power piston providing access of lubricant to the walls of said working cylinder.

11. In percussive apparatus having a power generating agency of the internal combustion engine type, a working cylinder, the upper portion of which constitutes an explosion chamber, the central portion of said cylinder having a crank shaft journalled across it, a power piston, the upper portion of which operates in said explosion chamber and by means of an arched section in its mid-portion surrounding said crank shaft is connected to a lower guide piston movable in the lower portion of the working cylinder structure, a striking member projecting axially downwardly from said guide piston to provide an unobstructed free hammering action, an air compressor piston operating within said power piston and connected with said crank shaft, intake and discharge air valves located in the head of said air compressor piston and air discharge ports located in the walls of said compressor and power pistons, timed to coincide at critical points in the movement of said pistons to admit scavenging and fuel mixing air into the explosion chamber of the working cylinder above the power piston, through a switch back porting in the wall of said cylinder, said power piston and compressor piston having means for supplying a flow of jetting air to the head at the front end of the working cylinder.

12. In percussive apparatus having a power generating agency of the internal combustion engine type, a working cylinder, the upper portion of which constitutes an explosion chamber, the central portion of said cylinder having a crank shaft journalled across it, a power piston,

the upper portion of which operates in said explosion chamber and by means of an arched section in its mid-portion surrounding said crank shaft is connected to a lower guide piston movable in the lower portion of said working cylinder structure, a striking member projecting axially downwardly from said crank shaft, intake and discharge air valves located in the head of said air compressor piston, air discharge ports located in the walls of said compressor and power pistons, timed to coincide at critical points in the movement of said pistons to admit scavenging and fuel mixing air into the explosion chamber of the working cylinder above the power piston, through a switch back porting in the walls of said working cylinder, said working cylinder having a fuel injection port leading directly into the combustion chamber, an exhaust port covered and uncovered by the working piston at different stages in the stroke of the same, the crank containing portion of said working cylinder and the arched mid-portion of said power piston having slidingly engaging keying elements and means conjointly controlled by said compressor and power pistons for maintaining an expansible air cushion coupling between the heads of said pistons.

13. In percussive apparatus having a power generating agency of the internal combustion engine type, a working cylinder, the upper portion of which constitutes an explosion chamber, the central portion of said cylinder having a crank shaft journalled across it, a power piston, the upper portion of which operates in said explosion chamber and by means of an arched section in its mid-portion surrounding said crank shaft is connected to a lower guide piston movable in the lower portion of said working cylinder structure, a striking member projecting axially downwardly from said crank shaft, intake and discharge air valves located in the head of said air compressor piston, air discharge ports located in the walls of said compressor and power pistons, timed to coincide at critical points in the movement of said pistons to admit scavenging and fuel mixing air into the explosion chamber of the working cylinder above the power piston, through a switch back porting in the wall of said working cylinder, said working cylinder having a fuel injection port leading directly into the combustion chamber, an exhaust port covered and uncovered by the working piston at different stages in the stroke of the same, the crank containing portion of said working cylinder and the arched mid-portion of said power piston having slidingly engaging keying elements and means conjointly controlled by said compressor and power pistons for maintaining an expansible air cushion coupling between the heads of said piston and for passing air so compressed from said air cushion into the working cylinder above the free power piston, said working cylinder having a fuel injection port leading directly into the combustion chamber and an exhaust port controlled by said power piston.
